UNITED STATES PATENT OFFICE.

PHILIP DIEHL, OF ELIZABETH, NEW JERSEY.

CONSTRUCTION OF ELECTRIC MACHINES.

SPECIFICATION forming part of Letters Patent No. 299,117, dated May 27, 1884.

Application filed April 5, 1883. (No model.)

To all whom it may concern:

Be it known that I, PHILIP DIEHL, of the city of Elizabeth, in the county of Union and State of New Jersey, have made a certain new and useful Improvement in the Construction 5 of Electric Machines; and I do hereby declare that the following is a full, clear, and exact description and specification thereof.

My invention relates especially to that class 10 of electric machines to which power is transmitted by means of a belt; and its object is to provide a simple and effective means for adjustment in connection with such transmission. In machines of this character the results 15 are so largely affected by any variation in the tension of this driving-belt that a simple, certain, and easy method of adjusting and controlling such tension is necessarily a great advantage.

20 To illustrate the operation of my invention, I have shown in the accompanying drawings an application of it to an ordinary dynamo-electric generator, and in said drawings Figure 1 represents a side and Fig. 2 a top view 25 of such dynamo.

I propose to construct the machine so that it shall be adapted to supports, (preferably pivotal,) to provide it with such supports and with means of adjustment, so that the machine, 30 with its belt-wheel, shall be raised from or lowered onto the driving-belt, and the pressure on such belt either entirely removed or increased to nearly the full weight of the machine, or adjusted at will within these limits.

35 A practical and convenient method of doing this is shown in the drawings, where one end of the machine is supported by and turns freely on the fixed pivot *a*, which rests on the fixed standards *A A*, and the other end by 40 the movable pivot *b*, through the center of which passes the adjusting-screw *B*, secured at its base in a suitable socket. The driving-belt *d*, running in the direction of the arrows,

and driven, as usual, from a pulley on a fixed shaft, passes around the central belt-wheel, *D*. 45 As the adjusting-screw *B* is turned in either direction by its hand-wheel, the movable pivot *b* rises or falls, carrying with it one end of the machine, (the other end turning on the fixed pivot *a*.) and consequently causing the belt-wheel *D* to correspondingly press upon or relieve the belt. Both of these supports may be made adjustable, if desired. Another great advantage of this arrangement of pivotal supports is, that in case it is desirable to use very 50 little horizontal space the dynamo may be swung up into a vertical position and the adjusting device secured to a vertical support, similar to that shown by the dotted lines in Fig. 1. With such an arrangement of the dynamo, it will be understood that the machine 55 will be hinged to the support or bracket, which is indicated by the dotted lines, and that the adjusting device will be secured to a similar support or bracket arranged overhead, thus 60 allowing the adjustable upper end of the machine to be moved in an arc of a circle.

I claim as my invention—

1. An electric machine having a driving-pulley, in combination with pivotal supports 70 for said machine, and with means for adjusting the height of one of said supports, and thus varying the tension of the driving-belt for said pulley, substantially as described.

2. An electric machine having a driving-pulley, and constructed with a fixed pivotal support at one end and an adjustable support at the other, combined with means for changing the height of said adjustable support, and thus varying the tension of the driving-belt for the 80 said pulley, substantially as described.

PHILIP DIEHL.
